TOILET PAPER STORAGE AND DISPENSER

Chester S. Deffenbaugh, Miranda, Calif.

Application June 29, 1951, Serial No. 234,337

6 Claims. (Cl. 242—55.3)

1

An object of my invention is to provide a toilet paper storage and dispenser which is designed to hold a number of spare rolls of toilet paper in readiness to be used as needed as well as support the roll in use. The usual toilet paper roll supporter and dispenser carries but the single roll and when this is consumed, it is necessary to remove the center tube of the used roll and substitute a new roll in the dispenser. An awkward situation arises should a guest be the one to use the last paper on a practically consumed roll. Once in awhile the supply of new rolls in storage is depleted through negligence or an oversight and it is necessary to make a new purchase at the store before a fresh roll can be added to the dispenser.

It is possible to buy toilet paper in individually wrapped rolls or to purchase a number of rolls in a single package. In the latter case, four rolls are customarily packed in a single wrapping. I have designed the storage compartment of my device to hold at least two extra rolls in addition to the one being used. It is a simple matter to increase the length of the container for holding a supply of three new rolls beside the one in use and therefore my device can take care of the four rolls which can be purchased in a single package.

A further object of my invention is to provide a device of the type described in which novel means is used for feeding one new roll at a time into a dispensing position as fast as the roll in use is consumed. The other rolls in the storage compartment are held against movement during the movement of the new roll into dispensing position. A window in the container permits the reserve supply of new rolls to be checked so that additional rolls can be added to the storage compartment when it is seen that the supply is getting low.

Other objects and advantages will appear in the following specification, and the novel features of the device will be particularly pointed out in the appended claims.

My invention is illustrated in the accompanying drawings forming a part of this application, in which:

Figure 1 is a side elevation of the device showing the cover in partially open position in dot dash lines, and the casing received in a cavity provided in a wall so that the front of the casing lies flush with the wall;

Figure 2 is a front elevation of the device with a portion of the toilet paper roll in use being shown in section in order to illustrate how the roll is rotatably supported;

Figure 3 is a top plan view of the device with the casing being received in the wall cavity and only the closed cover projecting out into the room;

2

Figure 4 is a vertical section through an empty casing and cover and is taken along the line IV—IV of Figure 2, the positions normally occupied by the rolls of toilet paper within the casing and cover being indicated by the dot dash circles;

Figure 5 is a transverse section taken along the line V—V of Figure 2; and

Figure 6 is an enlarged vertical section, portions being shown in elevation, and is taken along the line VI—VI of Figure 4.

While I have shown only the preferred form of my invention, it should be understood that various changes or modifications may be made within the scope of the appended claims without departing from the spirit and scope of the invention.

In carrying out my invention, I provide a casing indicated generally at A in Figures 1, 3, 4 and 5. This casing is in the form of a rectangular box, except that its lower rear wall is rounded as at 1 in Figure 1. The casing top indicated at 2 is flat and the rear wall 3 extends in a vertical direction and lies in a flat plane with the exception of the lower rounded portion 1 already referred to. Figure 3 indicates the casing as having flat side walls 4 and 5 that extend at right angles to the rear wall 3 and are disposed in vertical planes. The lower portions of the side walls 4 and 5 are rounded at their rear edges so as to conform to the rounded portion 1 of the rear wall.

The entire front of the casing A is open and the device is designed to be placed within an opening 6 in a wall B so that the entire casing A will be concealed by the wall and the rim 7 of the open front of the casing will lie flush with the wall surface as indicated in Figures 1, 3 and 4. The casing may be secured to the wall in any desired manner. I have shown the casing provided with lugs 8 that preferably lie in the plane of the rim 7 and screws 9 or other suitable fastening means may be used for securing the casing to the wall. The height of the casing is such as to receive three or more rolls of toilet paper arranged one above the other and the width of the casing is slightly in excess of the length of one of the rolls.

The casing is provided with a cover indicated generally at C and this cover overlies the upper open portion of the casing, but does not completely extend over the lower end of the casing. The opening provided by the rim 7 of the casing will therefore have its lower portion uncovered so that the lowermost roll of toilet paper indicated at D can be used. The cover C has side walls 10 and 11 that will form a continuation of the side walls 4 and 5 of the casing A when the cover is in closed position shown by the full lines in Figure 1 and further shown in Figures 2, 3

and 4. The side walls 10 and 11 have offset portions 10a and 11a that parallel the side walls 4 and 5, and slidably contact with their inner surfaces. The offset portions 10a and 11a are pivoted to the walls 4 and 5 of the casing A at 12.

In Figure 1, I show the cover C in closed position in full lines and indicate the same cover as in partially opened position by the dot dash lines. In order to prevent the cover C from opening too far, I provide pivot links E that are pivoted at 13 to the casing A and at 14, to the cover C. When the cover is fully opened, it is possible to insert a new roll of toilet paper through the opening thus provided.

In Figures 2 and 4, I show a pair of flat and elongated toilet roll gripping members F and these members extend substantially throughout the length of the casing when the cover is closed and their lower ends terminate at about the same place where the hinges 12 for the cover are disposed. The gripping members F normally lie in spaced and parallel arrangement with respect to each other and are also spaced inwardly from the side walls 10 and 11 of the cover a slight distance as shown in Figure 2. Both Figures 2 and 5 illustrate how the offset portions 10a and 11a of the cover are provided with inwardly extending hinge type lugs 15 and 16 that receive pivot pins 17 and 18. The gripping members F have bearings 19 and 20 through which the pins 17 and 18 extend. It will be seen from this construction that the toilet roll gripping members F are pivotally supported to the cover C and can swing about horizontal axes within certain limits as will presently be shown.

In Figure 1, I show the front wall 21 of the cover C having a curved top portion 21a that extends to the top wall 2 of the casing A when the cover is closed. The front wall 21 of the cover has its lower edge 21b disposed a considerable distance above the lower front edge 7a of the rim 7 of the casing A. The space thus provided between the edges 7a and 21b is sufficient to expose the roll of toilet paper D that is being used. Figure 2 illustrates how the lower ends of the roll gripping members F project below the edge 21b of the cover so as to bring the roll of toilet paper into view. These lower ends of the members F carry inwardly extending trunnions 22 that are designed to rotatably receive the lowermost roll of toilet paper D.

The diameter of the trunnions 22 is much smaller than the inner diameter 23 of the roll D and therefore I provide supporting discs G that may be removably mounted in the ends of the bore 23 of the roll D and these discs have openings 24 for rotatably receiving the trunnions 22. The supporting discs G also have flanges 25 that bear against the ends of the roll and limit the depth to which the reduced portions of the discs enter the central bore of the roll. The lower ends of the gripping members F bear against the outer surfaces of the flanges 25 mounted in the roll D. I preferably provide additional supporting discs G and insert these in the auxiliary rolls of toilet paper that are stored in the casing A in a manner hereinafter described.

It will be seen that the thickness of each flat and elongated gripping member F tapers from a fairly large butt at the lower end to a relatively small thickness at the top. The purpose of this is to make the upper end of each gripping member more flexible than the lower end. Figure 2 shows the inner surfaces of both members F

provided with brackets 26 that extend toward each other and are disposed above the roll D which is in use so as to support a storage roll D1 in spaced relation above the roll D, see Figure 1. It is possible to mount a second storage roll D2 in the casing A and have it rest upon the first or lowermost storage roll D1. Both storage rolls D1 and D2 are disposed between the gripping members F and the rolls are provided with the supporting discs G so that these gripping members will contact with the members G.

It will further be seen from Figure 2 that the pivots 17 and 18 for the gripping members F are placed opposite the lowermost storage roll D1. I provide U-shaped springs 27, see Figure 2, that extend between the offset portions 10a and 11a of the cover C and the adjacent portions of the gripping members F and urge the lower ends of the gripping members toward each other, i. e., the ends extending below the pivot points 17 and 18. The force of the U-shaped springs 27 is sufficient to create a braking action on the supporting discs G and tend to retard the rotation of the roll D which is in use as the paper is unwound therefrom.

I provide novel means for freeing the tubular cardboard core 28 of the roll D from the trunnions 22 after the paper has been used from the core. Referring to Figures 2 and 4, it will be seen that I provide a handle 29 that is rotatably mounted on the front wall 21 of the cover C and which may be manually turned. A lever 30 is secured to the handle on the inner side of the front cover wall 21, see Figure 4, and this lever is rotated with the handle. Links 31 and 32 extend from the free ends of the lever 30 to other levers 33 and 34 that are pivotally carried by the offset portions 10a and 11a of the cover C. The lever 33 is pivoted at 35 to the offset portion 10a and the lever 34 is pivoted at 36 to the offset portion 11a. The free ends of the levers 33 and 34 are connected by eyelets 37 and 38 or other suitable fastening means to the roll gripping members F.

When the handle 29 is rotated in a counter-clockwise direction, when looking at Figure 2, the links 31 and 32 are moved toward each other and will swing the levers 33 and 34 so as to move the lower ends of the gripping members F away from each other. This movement is sufficient to remove the trunnions 22 from the bores 24 of the members G and permit the used roll D with the members G to drop clear of the machine by passing through the opening provided between the edge 21b of the cover C and the edge 7a of the casing A. This same movement of the lower ends of the gripping members F away from each other will also remove the brackets 26 from under the first or lowermost storage roll D1. This storage roll is not under any appreciable clamping action from the members F even though the lower ends of the members have been moved away from each other to free the used roll. This lack of clamping action on the first or lowermost storage roll D1 is due to the fact that this roll is disposed between the pivot points 17 and 18 of the gripping members F and any movement of the gripping members about their pivot points will not affect these portions. Even though the lower ends of the members F have been moved far enough apart to free the lowermost used roll D, there will be no increased gripping action on the lowermost storage roll D1. The weight of the

first storage roll D1 will therefore be sufficient to cause it to drop by gravity toward the bottom of the casing A when the brackets 26 are removed from supporting it.

A person may hold his hand in the opening X at the bottom of the casing to catch and position the roll as it moves downwardly by gravity. The lowermost storage roll has already been provided with the supporting discs G and the person holds the roll so as to align the openings 24 in the discs with the trunnions 22. When the alignment of the trunnions 22 with the openings 24 is assured, the person can release his hold on the handle 29 and permit the springs 27 to move the lower ends of the members F toward each other and cause the trunnions 22 to enter the openings 24 of the discs G in the new roll.

The purpose of tapering the gripping members F throughout their lengths is to make their upper ends thin and resilient so as to yieldingly engage with the second storage roll D2 when the lower ends of the gripping members are moved away from each other for freeing the used roll D. It will be seen that when the lower ends of the members F are moved away from each other to free the used roll of toilet paper D, the upper ends of the same members F will be moved toward each other and since they are thin and therefore resilient, these ends will frictionally engage with the second storage roll D2 and hold this roll against downward movement even while permitting the lowermost storage roll D1 to move downwardly by gravity. In this way only one new roll will be moved into a position to take the place of the used roll. As soon as the new roll D1 does take the place of the used roll D and the person releases the handle 29 and permits the members F to return to normal position, the upper ends of the same members will move away from the top storage roll D2 and permit this roll to drop by gravity until it rests on the brackets 26.

In this simple way one roll at a time can be fed to the lower portion of the device where the new roll can be mounted in proper position in the manner already described. The length of the casing can be increased to hold three storage rolls rather than two as illustrated. If three rolls are held in storage, the tops of the members F would be lengthened to engage with the third roll in the same manner as has been explained for the engagement by the members F with the second roll D2. The two top storage rolls would be held against downward movement and only the lowermost storage roll would be freed to take the place of the used roll.

The device makes a neat appearance in a bathroom or other place where such a device is used, because the entire casing A is hidden from view. Only the cover C is viewable. The cover C has a push button 39 at its top, see Figure 4, for depressing a spring catch 40 that yieldingly secures the cover to the casing A in closed position. When a person wishes to add new storage rolls of paper to the casing, the button 39 is depressed and the cover opened. This will give access to the interiors of both the casing and cover. The rolls are first provided with the supporting discs G and then they are moved downwardly into the casing so as to be received between the gripping members F. The cover may then be closed and Figure 4 illustrates how the rear wall 3 of the casing and the front wall 21 of the cover are spaced just a slight distance away from the storage rolls D1 and D2 so as

to act as guides for the storage rolls. The front wall 21 of the cover is preferably provided with an elongated window 41 for permitting a person to view the interior of the casing and determine how many storage rolls of paper are housed within the casing.

It is possible to provide two hooks (not shown) at the top of the casing A for storing the extra supporting discs G when not in use.

10 I claim:

1. A device of the type described comprising a casing having an open front lying in a vertical plane; a cover hinged at its lower end to the casing and normally closing the greater portion of the open front of the casing, from the top of the casing to a spaced distance from the bottom thereof; a pair of toilet roll gripping members pivotally carried by the cover and arranged along the sides of the cover so as to overlie the ends of the rolls; means carried by the lower ends of the gripping members for rotatably supporting a roll of toilet paper in a position where access may be had to the roll through the opening provided by the uncovered lower portion of the casing; spring means for urging the lower ends of the gripping members into frictional engagement with the roll being used; and auxiliary roll-supporting brackets carried by the gripping members for supporting stored rolls between the gripping members and above the bottom roll being used.

2. In a device of the type described: a pair of toilet roll gripping members vertically arranged and spaced apart in parallel relation so as to grip the ends of a plurality of toilet rolls disposed one above the other and between the members; a horizontally disposed pivotal support for each member; means carried by the lower ends of the gripping members for rotatably supporting a roll of toilet paper in a position for use; spring means for urging the lower ends of the gripping members toward each other for frictionally engaging the roll supported by said roller carrying means; auxiliary roll-supporting brackets carried by the gripping members at a point for supporting the lowermost stored roll in a position between the gripping members and near the pivotal supports and above the roll being used; said gripping members extending a sufficient distance above the first stored roll to receive at least one more roll for storing, this roll resting on the first mentioned stored roll and having its ends positioned between the gripping members.

3. In a device of the type described: a pair of toilet roll gripping members vertically arranged and spaced apart in parallel relation so as to grip the ends of a plurality of toilet rolls disposed one above the other and between the members; a horizontally disposed pivotal support for each member; means carried by the lower ends of the gripping members for rotatably supporting a roll of toilet paper in a position for use; spring means for urging the lower ends of the gripping members toward each other for frictionally engaging the roll supported by said roller carrying means; auxiliary roll-supporting brackets carried by the gripping members at a point for supporting the lowermost stored roll in a position between the gripping members and near the pivotal supports and above the roll being used; said gripping members extending a sufficient distance above the first stored roll to receive at least one more roll for storing, this roll resting on the first mentioned stored roll and having its ends positioned between the gripping members; means for swing-

ing said gripping members about their pivots for moving the lower ends away from each other when it is desired to free the lowermost roll from the members; the first mentioned stored roll being free to move downwardly by gravity to occupy the position formerly occupied by the roll being used, and the next roll above the said first mentioned stored roll being held against downward movement by the upper ends of the gripping members being urged inwardly and gripping said 10 roll due to the outward swinging of the lower ends of the gripping members.

4. A device of the type described comprising a casing having an open front lying in a vertical plane; a cover having sides and being hinged to the casing and closing the open front with the exception of the lower portion so that a roll of toilet paper can pass through this uncovered lower portion even when the cover is closed; a pair of flat and elongated toilet roll gripping members pivotally secured in spaced relation to the sides of the cover and extending substantially throughout the length of the casing when the cover is closed; the flat sides of the gripping members paralleling the sides of the cover and the members being spaced far enough apart to receive toilet paper rolls therebetween so that the ends of the rolls are disposed adjacent to the inner surfaces of the members; trunnions carried by the lower ends of the members; yielding means for urging the lower ends of the members toward each other so that the trunnions will enter the ends of the toilet roll bore and will rotatably support the roll; brackets mounted on the members above the trunnion supported roll and extending inwardly for supporting an extra roll of toilet paper; the pivotal supports for the members being positioned where the extra roll is supported by the brackets; the upper ends of the members being adapted to receive at least one additional roll for storage, this roll resting on the said first mentioned extra roll and having its ends disposed between the members; and means for swinging the lower ends of the members away from each other for freeing the trunnion supported roll when the latter is used, this movement releasing the brackets from the first mentioned extra roll and permitting it to drop by gravity into a position for connection with the trunnions; the upper ends of the members gripping the second mentioned additional roll and preventing it from dropping; the members when freed from the swinging means, causing the trunnions to support the extra roll and permitting the additional roll to move down and be supported by the brackets.

5. A device of the type described comprising a casing having an open front lying in a vertical plane; a cover having sides and being hinged to the casing and closing the open front with the exception of the lower portion so that a roll of toilet paper can pass through this uncovered lower portion even when the cover is closed; a pair of flat and elongated toilet roll gripping members pivotally secured in spaced relation to the sides of the cover and extending substantially throughout the length of the casing when the cover is closed; the flat sides of the gripping members paralleling the sides of the cover and the members being spaced far enough apart to receive toilet paper rolls therebetween so that the ends of the rolls are disposed adjacent to the inner surfaces of the members; trunnions carried by the lower ends of the members; yielding

means for urging the lower ends of the members toward each other so that the trunnions will enter the ends of the toilet roll bore and will rotatably support the roll; brackets mounted on the members above the trunnion supported roll and extending inwardly for supporting an extra roll of toilet paper; the pivotal supports for the members being positioned where the extra roll is supported by the brackets; the upper ends of the members being adapted to receive at least one additional roll for storage, this roll resting on the said first mentioned extra roll and having its ends disposed between the members; and means for swinging the lower ends of the members away from each other for freeing the trunnion supported roll when the latter is used, this movement releasing the brackets from the first mentioned extra roll and permitting it to drop by gravity into a position for connection with the trunnions; the upper ends of the members gripping the second mentioned additional roll and preventing it from dropping; the members when freed from the swinging means, causing the trunnions to support the extra roll and permitting the additional roll to move down and be supported by the brackets; said gripping members being gradually reduced in thickness from their lower ends to their tops so that the upper ends of the members will flex and yieldingly engage with the ends of the second mentioned additional roll.

6. A device of the type described comprising a casing having an open front lying in a vertical plane; a cover having sides and being hinged to the casing and closing the open front with the exception of the lower portion so that a roll of toilet paper can pass through this uncovered lower portion even when the cover is closed; a pair of flat and elongated toilet roll gripping members pivotally secured in spaced relation to the sides of the cover and extending substantially throughout the length of the casing when the cover is closed; the flat sides of the gripping members paralleling the sides of the cover and the members being spaced far enough apart to receive toilet paper rolls therebetween so that the ends of the rolls are disposed adjacent to the inner surfaces of the members; trunnions carried by the lower ends of the members; yielding means for urging the lower ends of the members toward each other so that the trunnions will enter the ends of the toilet roll bore and will rotatably support the roll; brackets mounted on the members above the trunnion supported roll and extending inwardly for supporting an extra roll of toilet paper; the pivotal supports for the members being positioned where the extra roll is supported by the brackets; the upper ends of the members being adapted to receive at least one additional roll for storage, this roll resting on the said first mentioned extra roll and having its ends disposed between the members; means for swinging the lower ends of the members away from each other for freeing the trunnion supported roll when the latter is used, this movement releasing the brackets from the first-mentioned extra roll and permitting it to drop by gravity into a position for connection with the trunnions; the upper ends of the members gripping the second mentioned additional roll and preventing it from dropping; the members when freed from the swinging means, causing the trunnions to support the extra roll and permitting the additional roll to move down and be supported by the brackets, and removable supporting discs and

adapted to be received in the ends of the rolls and to enter the ends of the central bores in the rolls a slight distance; said discs having openings for rotatably receiving the trunnions.
